UNITED STATES PATENT OFFICE.

SATO HISANOSUKE, OF NEW YORK, N. Y.

GAME APPARATUS.

Application filed September 18, 1926. Serial No. 136,234.

The present invention is concerned with the provision of a game apparatus which will be both interesting and amusing to old and young alike.

5 It finds its preferred embodiment in a unique type of apparatus in which a movable member mounted upon an eccentrically rotatable table is shifted by the action of the table into any one of a series of identified pockets or compartments, means being preferably provided for manually rotating the table to actuate the movable member in a chance determined direction toward one of the pockets.

15 More specifically, the movable member is in the nature of a top caused to spin or to move while spinning about the surface of the table due to the eccentric movement of the latter, and the means for eccentrically 20 rotating the table preferably includes a hand wheel or motor acting through suitable gearing to drive an eccentric.

Objects of the invention are to provide an amusing game apparatus of this character which will be of simple, practical construction, rugged and durable in use, neat and attractive in appearance, easy to manipulate, and inexpensive to manufacture.

With the above noted and other objects 30 in view, the invention consists in certain novel features of construction and combinations and arrangements of parts, as will be more fully hereinafter set forth and pointed out in the claims. The invention may be 35 more fully understood from the following description in connection with the accompanying drawings, wherein—

Fig. 1 is a top plan view of the apparatus.

40 Fig. 2 is a vertical sectional view therethrough on the line 2—2 of Fig. 1.

In the drawings the numeral 10 represents the base of the apparatus which may be of any desired shape and construction. As illustrated it is in the nature of a box-like 45 housing which conceals the driving gears for the eccentric turntable 11 mounted above the base. Preferably a stub shaft 12 vertically mounted in the central portion of 50 the base member carries at its upper end a circular eccentric 13 working in a depending bearing sleeve 14 carried by the turntable. The lower end of the stub shaft may 55 carry a bevelled pinion 15 meshing with a pinion 16 on a horizontal drive shaft 17. Shaft 17 may be supported in bearings 18

in the base 10 and in a bearing 19 carried by bracket 20 secured to the interior of the base. Shaft 17 is driven either through the instrumentality of a motor or through a 60 hand wheel such as 21 disposed at the exterior of the base.

Preferably the turntable 11 is not supported directly upon the eccentric 13, but is supported by a series of links 22 pivotally 65 connected to studs 23 projecting from the upper face of the base, and to studs 24 depending from the bottom of the turntable. The studs 23 and 24 may be in the nature of screws and may have associated therewith 70 spacer sleeves 25 to prevent any movement of the links 22 in a vertical plane.

The length of the links 22 is of course directly proportional to the throw of the eccentric, so that as the turntable is eccentrically rotated, the links 22 will rotate 75 about their pivots 23.

A movable element, such for instance as a top 30 is adapted to be supported on the turntable. An upstanding peripheral 80 flange 31 prevents the top from sliding off the edges of the table and near this flange are an annular series of pockets or openings 32 into any of which the top is adapted to enter. These pockets may be numbered with 85 certain values not illustrated, or certain of the pockets may be designated by stars or other identifying marks as shown.

In operation, the top is grasped and spun near the center of the turntable, the hand wheel is then grasped and rotated rapidly to cause an eccentric rotation of the turntable. This rotation will impart to every point on the turntable a relatively restricted circular motion, so that the top will be kept spinning 95 until such time as it works its way into one of the pockets.

If the top is properly proportioned, and sufficient speed is imparted to the turntable, the top may actually be picked up from a 100 central position and spun by the moving table beneath it.

The manner of scoring the game or the particular way in which the pockets are designated, of course is subject to a wide 105 range of variation, in fact numerous changes and alterations might be made in the general form and arrangement of parts described without departing from the invention. Hence I do not wish to limit myself to the 110 details set forth, but shall consider myself at liberty to make such changes and altera-

tions as fairly fall within the spirit and scope of the appended claims.

I claim:

1. A game apparatus including an eccentrically rotatable turntable upon which a movable member is adapted to be supported, and a series of devices adjacent the edges of the turntable into any of which the movable element is adapted to be directed by the eccentric rotation of the turntable.
2. A game apparatus including an eccentrically rotatable turntable upon which a movable member is adapted to be supported, and a series of devices adjacent the edges of the turntable into any of which the movable element is adapted to be directed by the eccentric rotation of the turntable, said movable element comprising a top adapted to be spun by the eccentric motion of the table.
3. A game apparatus including an eccentrically rotatable turntable upon which a movable member is adapted to be supported, and a series of devices adjacent the edges of the turntable into any of which the movable element is adapted to be directed by the eccentric rotation of the turntable, said table having openings therein near its periphery

adapted to serve as the receiving members for the top.

4. In a game apparatus, a turntable upon which a top is adapted to be supported, and means for eccentrically rotating the table to spin the top, said means including a shaft, an eccentric on the shaft received in a bearing sleeve depending from the table.

5. In a game apparatus, a turntable and means for eccentrically rotating the table, said means including a shaft, an eccentric on the shaft received in a bearing sleeve depending from the table, and means for supporting the table independently of the eccentric.

6. In a game apparatus, a turntable and means for eccentrically rotating the table, said means including a shaft, an eccentric on the shaft received in a bearing sleeve depending from the table, and means for supporting the table independently of the eccentric, comprising links pivotally connecting the bottom of the turntable to stationary studs below the table, whereby the links are rotated about the stationary studs as the turntable is actuated by the eccentric.

SATŌ HISANOSUKE.
